United States Patent Office.

B. BRIODY, OF DETROIT, MICHIGAN.

Letters Patent No. 78,048, dated May 19, 1868.

IMPROVEMENT IN ARTIFICIAL LIMBS.

The Schedule referred to in these Letters Patent and making part of the same.

TO ALL WHOM IT MAY CONCERN:

Be it known that I, B. BRIODY, of Detroit, in the county of Wayne, and State of Michigan, have invented a new and useful Improvement in Artificial Limbs; and I do hereby declare that the following is a full, clear, and exact description thereof, which will enable others skilled in the art to make and use the same, reference being had to the accompanying drawings, forming part of this specification.

The nature of my invention relates to improvements in artificial legs and feet, to be used in substitution of the human leg below the knee-joint, whereby it is designed to provide a more cheap and simple appliance, which is less liable to get out of order than those now in use, and it consists principally in the construction of the ankle and toe-joints, as will be more fully described on reference to the accompanying drawings, wherein—

Figure 1 represents a sectional elevation, and

Figure 2 represents a plan of the foot with the leg removed at the ankle-joint, and partially broken away to show the toe-joint.

Similar letters of reference indicate corresponding parts.

A represents the foot, B the ankle, and C the toes; *a* represents the pintle of a hinge-joint, which is secured to the foot A, in a socket, *b*, for securing the lower end of the ankle, by the bolts *d*, running through the foot to a socket, *e*, in the bottom of the same, where they are held by nuts *g*, screwed up against India-rubber, or other yielding washer. To the said pintle are jointed rods *h*, running upward, and terminating in the bottom of a socket formed in the leg above the ankle, where they are in like manner secured by nuts *g'*, and yielding washers *f'*.

D D are thick rubber springs, interposed between the bottom of the socket *b* and the end of the ankle, on either side of the hinge-joint.

The part C, representing the toes of the human foot, is jointed to the foot A in a similar manner by a single joint, *d² d²*, but are not socketed in the same manner, the rubber springs *F F* being arranged only above, that is, on the upper side of the joint. The contiguous surfaces of the parts A C are curved or rounded, as shown in the drawing.

The bottom of the foot may be covered by heavy canvas, leather, or any other material that will yield to action of the toe-joint; so also a strip of leather or canvas may be secured over the opening of the toe-joint, to prevent the entrance of dirt or other foul matter, and also to serve to prevent the spring *F* from throwing the toe part beyond the proper horizontal line of the foot after it is raised from the ground in the act of walking.

The springs *D D* are intended to be so adjusted, with reference to the parts A and B, that when the foot is raised from the ground they will hold the two parts at or about right angles to each other, but will yield in either direction, in the act of walking, while the foot is on the ground, sufficiently to allow the parts to move as in the natural foot, without halting or stiffness, and immediately restore them to the natural position when the foot is raised from the ground.

h represents a semicircular steel spring, interposed between the ankle-joint and the lower end of the ankle, in an inverted position, so that the edges of the same bear upon the upper faces of the parts *D D*, whereby any looseness of the joint, in a vertical direction, is taken up, so that when the foot is taken up from or set down upon the ground, no shock occurs, the said spring pressing the parts away from each other when raised from the ground, and yielding to the pressure of the same together when the foot rests on the ground.

By reason of the use of the yielding washers, under the nuts of the joint-bolts, the joints will readily yield in a lateral direction in walking on rough ground, when the foot is liable to tread unevenly, without undue strain upon the stump of the wearer, and will as readily restore the parts when the foot is raised again.

I claim as new, and desire to secure by Letters Patent—

1. The combination of the parts A and B, by means of a hinge joint, constructed substantially as and for the purpose described.

2. The combination of the parts A and C, by a hinge joint, substantially as and for the purpose described.
3. The combination, with the hinge-joint d d , constructed substantially as described, of the rubber or other yielding washer-springs f f' , as and for the purpose described.
4. The combination, with the parts A and B, and the hinge-joint as described, of the India-rubber or other yielding springs D D, substantially as and for the purpose described.
5. The combination, with the parts A and C, and their hinge-joints d^2 d^2 , of the rubber or other yielding springs F, substantially as and for the purpose described.
6. The combination, with the parts A and B, jointed together as described, of the semicircular spring h, substantially as and for the purpose set forth.
